(57) **CLAIM**

The ornamental design for a spray brush, as shown and described.

DESCRIPTION

FIG. 1 is a front, right and bottom perspective view of a spray brush, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a rear, left, and top perspective view thereof, shown with the brush head removed to show portions of the article not clearly visible when combined.

The broken lines shown in the drawings illustrate portions of the spray brush that form no part of the claimed design.
